UNITED STATES PATENT OFFICE

HARVEY J. DIVEKEY, OF AURORA, ILLINOIS, ASSIGNOR TO ILLINOIS SUPPLY COMPANY, OF AURORA, ILLINOIS, A CO-PARTNERSHIP COMPOSED OF HARVEY J. DIVEKEY, WILLIAM M. WILLETT, SR., AND WILLIAM M. WILLETT, JR.

AIR CIRCULATOR AND HEATER

Application filed April 28, 1930. Serial No. 447,936.

My present invention relates to improvements in heaters and air circulators for poultry houses. It has been my object to produce a simple and economical structure for heating and circulating the air in poultry houses which will take up a minimum space and will interfere as little as possible with the movement of the fowls and which will require very little attention to keep it in operation.

Unheated poultry houses, for introduction into which my device is designed, are not uncommonly extremely damp and their effective and wholesome heating can only be accomplished when provision is made for securing an ample circulation of the heated air.

I have attained the above indicated objects of providing facilities for circulating and heating the air in poultry houses by means of the structure illustrated in the accompanying drawing, in which—

Figure 1 is an elevation of an air heating and circulating device embodying my invention, a portion thereof being broken away to indicate the interior arrangement;

Fig. 2 is a vertical central cross section of the structure shown in Fig. 1; and

Fig. 3 is a section on line 3—3 of Fig. 1.

Similar reference characters designate similar parts throughout the respective views.

I employ the same principle in creating and maintaining a circulation of the air as is employed in the construction of a tall chimney or stack for the creation of draught for fire and in the employment of this principle

I provide a vertical radiator consisting of a bottom header 5 and a considerably larger top header 6, which headers are connected by a plurality of vertically disposed tubes or pipes 7. I prefer to cast the headers and em-

ploy a suitable size and quality of commercial pipe for the tubes 7, the pipe and headers being preferably welded together. The lower header 5 has provided on the lower side thereof embossments 8 which are bored and tapped to receive sections of pipe 9, which perform the function of legs or standards. On the bottoms of the legs or standards 9 are provided T's 10 into the arms of which screw sections of tubing 11 upon the outer ends of

for the structure. The standards 9 and the associated parts forming the support of the radiator are of sufficient height to permit the fowls to pass freely under the radiator and also to afford ample space for the circulation 55 of air upwardly around the radiator.

An end tube 7a depending from the upper header 6 is shown in Fig. 1 connected with the top or discharge port of an oil burning water heater 13, and the lower header 5 is 60 connected with the return to the same water heater. The reason for making the top header 6 larger than the bottom header 5 is to provide a relatively considerable air space in connection with the system containing the 65 heated water so that this air expanding as the water heats will create pressure and permit of attaining a heat considerably over the normal boiling temperature without boiling the water in the system.

To fill the system without getting air into the pipe which would create air locks and prevent the desired circulation, I provide a pipe 21 leading from the end of the lower header 5 opposite to that end of the header connected 75 with the water heater, which pipe leads above the upper header 6 and is closed by a screw cap 22. At about the center of one end of the upper header I provide an overflow pipe 23 with a valve or cock 24. To fill the system 80 the valve or cock 24 is opened and the cap 22 removed and water poured into the tube 21 until the water discharges from the overflow pipe 23. The cap 22 is then screwed onto the pipe 21 and no further filling is usually required throughout a season's use.

I have included in the run of pipe designated as 7a a safety pressure gauge 14 to prevent an explosion in the event that, through mischance, the temperature in the 85 system should get too high. The vertical radiator, as heretofore described, will heat the air and create some circulation without any additional features, but its air circulating properties are greatly increased by enclosing 90 the radiator between the side plates 15—15, which renders the structure very similar in operation to the operation of a stack or chimney except that my present apparatus is more effective than a stack or chimney of equal 95 100

length in that the air is heated and caused to rise throughout its entire length.

I have shown and described an oil burning water heater 13 associated with my device.

5 A gas or other heater could be used equally well in connection with my invention. I have illustrated my invention in association with an oil burning water heater merely because dependable oil heaters requiring only an adjustment of the fuel supply to secure a desired temperature may be purchased on the market.

15 The side plates 15 may be assembled with the radiator by means of spacing blocks 16 set between the tubes of the radiator, the ends of which blocks are bored and tapped to receive stud bolts 17 extending through perforations in the plates 15, which plates are secured to the spacing blocks by nuts 18.

20 It has generally been found desirable to provide the fowls with warmed drinking water, and for this purpose I supply the water troughs 19 which are perforated near the tops of their back walls to engage studs 20 provided near the bottoms of the plates 15. As there is practically no evaporation from the radiator or the heater one filling thereof has been found ample for the season's use and a several days' supply of fuel may be provided for the heater. It will be seen that my heater requires very little attention to maintain it in operation.

25 As the legs support my device sufficiently above the floor to permit the fowls to pass under it, I provide a shelf or perch for the support of the fowls when they are drinking from the troughs. Laterally extending bars 19^a are secured to the legs 9 in any suitable way and to the ends of these bars are secured shelf or perch pieces 20 upon which the fowls stand when they are drinking out of the troughs.

30 The provision of a vertical radiator with side plates, as described and illustrated, secures a continuous circulation of heated air throughout a building of considerable extent which will both warm and dry the air in the building and produce very much improved and more healthful living conditions for the fowls.

35 Having described my invention what I claim as new and desire to secure by Letters Patent is:

1. A heater and air circulator for poultry houses comprising a pair of parallel spaced, horizontally disposed, elongated chambers, the upper of said chambers being of larger capacity than the lower, a series of vertically disposed tubes extending and providing communication between said chambers, plates spaced from and secured upon opposite sides of said lower chamber and communicating tubes, supports associated with said lower chamber for supporting said structure in spaced relation with the floor, and an inlet

connection for said upper chamber and an outlet connection for said lower chamber aligning with the bottoms of said respective chambers.

2. A heater and air circulator for poultry 70 houses comprising a vertically disposed elongated radiator provided with an air chamber at the top thereof, plates spaced from and secured upon opposite sides of said radiator, means for supporting said radiator in vertical position in spaced relation from the floor, and an inlet connection for said upper chamber and an outlet connection for said lower chamber aligning with the bottoms of said 75 respective chambers.
